UNITED STATES PATENT OFFICE.

JOHN UBL AND PAUL VOYDISECK, OF NEW YORK, N. Y.

CLOTHES-DRIER.

No. 797,242.

Specification of Letters Patent.

Patented Aug. 15, 1905.

Application filed July 19, 1904. Serial No. 217,261.

To all whom it may concern:

Be it known that we, JOHN UBL, a citizen of the United States, and PAUL VOYDISECK, a subject of the Emperor of Austria-Hungary, both residing at New York, in the county of New York and State of New York, have invented certain new and useful Improvements in Clothes-Driers; and we do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to clothes-driers which are intended for outdoor use, and particularly in cramped locations between large buildings. It has a traveling endless line, each part of which can be readily brought to any point in its circuit. The line-supports may be located so that the line will run in any direction from vertical to horizontal. For this reason it may extend many stories in height.

The accompanying drawings illustrate the invention, its various features being referred to by letters, similar letters denoting corresponding parts in both views.

Figure 1 in the drawings is a side elevation of the device with its support shown fragmentarily. Fig. 2 is a vertical section of the pulley on line $\alpha\alpha$ of Fig. 1.

The letter A designates a strong screw eye or bolt having an eye at its outer end. This bolt is to be screwed or driven into a post or other object and supports the pulley mechanism.

B is what we have denominated a "bell pulley" from its resemblance to a bell. It has an upper section or body b, a widely-flaring lower section b', and a rope-groove b' between said sections.

C is a vertical screw-bolt constituting the shaft on which the pulley revolves. It extends upward through a central opening in the pulley and on successively through a nut d, a jam-nut d', a cap e, the above-mentioned screw-eye A, and a top nut f, which is tightened down upon the eyebolt A. We prefer to use

ball-bearings with this pulley, one set of balls g being located between the head c of the bolt C and a cone c' seated in the lower part of the body of the pulley, and another set of balls g' between a cone in the upper part of said body and the nut d next above. The lower edge of the cap e extends below the upper edge of the bell-pulley in order to prevent rain and dust from entering the bearings.

H is the clothes line or rope on which are hung the articles to be dried.

The enlargement of the pulley below the rope-groove permits considerable increase in length of the rope without its leaving the pulley, and the screw-eyes may be partly withdrawn from or be screwed farther into the retaining wall or pole, thereby varying the distance between the opposite pulleys. It is evident that these pulleys may be located so that the rope may extend in any direction.

Having described our invention, what we claim, and desire to secure by Letters Patent of the United States, is—

1. A clothes-drier comprising a pulley having a groove for the clothes-line, a vertical shaft in said pulley, a supporting screw-eye to which said shaft is attached and a cap on said pulley whose lower edge overlaps the upper edge of the pulley as described.

2. A clothes-drier comprising a pulley adapted for ball-bearings and formed with an upper body-section, a widely-flaring lower section and a rope-groove therebetween, a vertical supporting-shaft through said pulley, a nut on said shaft resting on the upper face of said upper body-section, a jam-nut on said nut, a cap through which said bolt passes, the edge of said cap overlapping the upper edge of said body-section, a screw-bolt having an eye through which said shaft passes and a nut to tighten said screw-bolt upon said cap, substantially as herein set forth.

In testimony whereof we affix our signatures in presence of two witnesses.

JOHN UBL.

PAUL VOYDISECK.
